UNITED STATES PATENT OFFICE

103,874

DESIGN FOR AN AIR CONDITIONING CABINET

Robert D. Lambert, New York, and Matson C. Terry, New Rochelle, N. Y., assignors to American Radiator Company, New York, N. Y., a corporation of New Jersey

Application February 26, 1937, Serial No. 67,879

Term of patent 14 years

To all whom it may concern:

Be it known that we, Robert D. Lambert and Matson C. Terry, citizens of the United States, and residents, respectively, of the city, county, and State of New York, and of New Rochelle, in the county of Westchester and State of New York, have invented a new, original, and ornamental Design for an Air Conditioning Cabinet, of which the following is a specification, reference being had to the accompanying drawing, forming part thereof.

In said drawing—

Fig. 1 is a perspective view of an air conditioning cabinet embodying our new design; and Fig. 2 is a top plan view thereof.

We claim:—

The ornamental design for an air conditioning cabinet, as shown.

ROBERT D. LAMBERT.
MATSON C. TERRY.
